UNITED STATES PATENT OFFICE.

TOMASE B. JACHIMIAK AND JOSEF KENDZIERSKI, OF SOBIESKI, WISCONSIN.

LIFTING DEVICE.

SPECIFICATION forming part of Letters Patent No. 590,840, dated September 28, 1897.

Application filed April 10, 1897. Serial No. 631,527. (No model.)

To all whom it may concern:

Be it known that we, TOMASE B. JACHIMIAK and JOSEF KENDZIERSKI, of Sobieski, in the county of Oconto and State of Wisconsin, have invented a new and useful Improvement in Lifting Devices, of which the following is a description, reference being had to the accompanying drawings, which are a part of this specification.

10 Our invention has relation to improvements in lifting devices.

The invention is particularly adapted for use as a stump puller or extractor. In fact, it combines, essentially, the features of a 15 combined stump-extractor and lifting-jack.

The primary object had in view is to secure by a simple combination and arrangement of parts the maximum power; and with this end in view the invention consists of the devices 20 and parts, or their equivalents, as hereinafter more fully set forth.

In the accompanying drawings, Figure 1 is a front elevation of the complete machine. Fig. 2 is a view at right angles to Fig. 1. 25 Fig. 3 is a vertical longitudinal sectional view of the machine. Fig. 4 is a vertical section of the upper portion of the machine, taken on a plane at right angles to the section of Fig. 3; and Fig. 5 is a plan view with 30 the upper portion of the casing in section.

The frame of the machine advisably consists of a base-piece 6 and inclined front and rear standards 7, extending upwardly from the base-piece and connected at their upper 35 ends by a connecting-piece 8. Surmounting this connecting-piece 8 is a casing 9, preferably rectangular in form.

Journalized in opposite end pieces of the casing 9 is a worm-shaft 10, said shaft being 40 journaled at one end in an elongated opening 11. The end of the shaft which projects through this opening to the outside of the casing passes through a pivoted lever 12, the extremity of the shaft being provided with 45 an operating-handle 13. The outer end of the lever is provided with a slot 14, which is adapted to be normally engaged by an inwardly-projecting lug 15 of a spring-arm 16, the lower end of said spring-arm being secured to the end piece of the casing.

The numeral 17 indicates a worm-wheel which is located below the worm-shaft and

between two longitudinal beams 18 and 19. When the inwardly-projecting lug 15 of the spring-arm 16 is engaging the slot 14 of the 55 lever 12, the worm-shaft is then in engagement with the worm-wheel. If, however, the spring-arm is pulled outwardly, so as to release its lug from engagement with the slot of the lever, the worm-shaft is free to be 60 raised in the elongated opening 11, so as to be brought out of engagement with the worm-wheel. The shaft may be allowed to remain in this position by permitting the spring-arm to spring back so that its lug 15 will engage 65 under the lever 12.

Arranged between the intermediate beam 19 and another side beam 20 is a shrouded pinion 21, consisting of the outer heads and intermediate head and the connecting bars 70 or spindles. The outer heads of this pinion are formed with projecting journals, one of which having its bearing in the beam 20 and the other extending through the intermediate beam 19 and to the beam 18 and forming the 75 axis for the worm-wheel 17, said wheel being mounted fast thereon. Also mounted between the beams 19 and 20 in advance of the shrouded pinion 21 is a lantern-wheel 22, the journals of said wheel having their bearings in 80 the beams 19 and 20. The end heads of this lantern-wheel are of sufficient width to enable cog-wheels 23 to be mounted thereon, said cog-wheels being advisably keyed thereto. The teeth of these cog-wheels mesh with 85 the respective bars or spindles of the shrouded pinion 21 and derive rotation therefrom, which rotation is of course imparted to the lantern-wheel 22.

Extending down from the under side of the 90 casing 9, at one end thereof, is a boxing 24. This boxing extends downwardly for a desired distance, preferably to the base-piece 6. Within this boxing is adapted to be vertically reciprocated a rack-bar 25, the teeth of 95 the rack being formed on the inner edge of the bar. The upper end of the rack-bar passes entirely through the upper casing 9 and through an opening in a removable top or cover 26. This top or cover is provided 100 with a hinged catch 27, the outer leaf of which projects beyond the cover and is provided with an opening through which the upper end of the spring-arm may pass. The

spring-arm therefore serves to hold the cover normally in place. The upper extremity of the rack-bar which projects above the cover is provided with a removable and preferably

- 5 revoluble head-piece 28, while the lower end of the rack-bar is formed with a projecting foot 29. This foot passes through and works in an elongated slot 30 in the outer side of the boxing 24. This slot therefore permits 10 the rack-bar to be vertically reciprocated. The rack-bar is so positioned that it passes between the cog-wheels 23 23, so that the teeth of the rack may mesh with the connecting bars or spindles of the lantern-wheel 22. 15 It will be noticed that the journal of the shrouded pinion 21, which forms the axis of the worm-wheel 17, extends out through the front piece of the casing 9 and has keyed thereon a ratchet-wheel 31, which is adapted 20 to be engaged by a pivoted dog 32.

In operation the foot of the rack-bar is made to engage with the object to be raised. In case, however, it is desired to pull the stump of a tree from the ground this foot is 25 preferably anchored to the stump by means of a chain wrapped around the stump and looped over the foot-piece. The operating-handle is now turned, and this through the described gearing, consisting of the worm- 30 shaft, worm-wheel, shrouded pinion, and cog-wheels, will cause an upward movement of the rack-bar through the engagement of the bars or spindles of the wheel 22 with the teeth of said rack-bar. It is obvious that by this 35 arrangement of gearing a most powerful leverage can be secured.

By the provision of the head-piece 28 at the upper end of the rack-bar the device can be conveniently used as a lifting-jack for elevating vehicle-axles and the like. The machine when so used is placed in such position 40 that the body to be raised rests on the head-piece 28. After raising a body to the desired height, if it is then desired to discontinue 45 using the machine, the outer leaf of the hinge-catch 27 is released from engagement with the upper end of the spring-arm 16. Said spring-arm is then pulled outwardly, so as to permit the raising of the lever 12, and the 50 consequent raising of the worm-shaft out of engagement with the worm-wheel, the lever and shaft being held in this raised engagement by permitting the spring-arm to spring back, so that its projecting lug will engage 55 under the lever. The rack-bar is now free to descend rapidly to its normal position. If mechanism were not provided for raising the worm-shaft out of engagement with the worm-wheel, it is obvious that the descent of the 60 rack-bar would be very slow and would have to be accomplished by turning the crank-handle. The ratchet-wheel 31 and engaging dog 32 serve to prevent reverse rotation of the axis of the worm-wheel, and thereby have 65 the effect of holding the rack-bar to its ad-

justed position. When it is desired that the rack-bar should descend, the dog of course is released from engagement with the ratchet-wheel.

What we claim as our invention is—

1. The combination, of a frame, a lever pivoted to the outer face of one of the side pieces of the frame, a worm-wheel within the casing, a worm-shaft having one end journaled in the frame, and its opposite end passing through an elongated slot in the frame and journaled in the pivoted lever, and an inwardly-springing spring-arm provided with an inwardly-extending lug, said lug adapted normally to engage the lever so as to maintain said lever in a position to hold the worm-shaft in engagement with the worm-wheel, and said lug when released from the lever adapted to permit said lever to be turned so as to disengage the worm-shaft from the worm-wheel, the parts being held in disengaged position by permitting the inwardly-extending lug of the spring-arm to engage the lever at a point other than its first point of engagement. 70

2. The combination of a casing, a lever pivoted to the outer side of said casing, a worm-wheel within the casing, a worm-shaft journaled in the casing, said shaft extending through an elongated opening in the casing 95 and through an opening in the lever, a spring-arm adapted to engage the lever so as to hold the worm-shaft in engagement with the worm-wheel, and when disengaged from the lever to permit of the raising of, and to support, the shaft out of mesh with the worm-wheel, a cover for the casing, and a catch secured to the cover and projecting therefrom, said catch provided with an opening through which the upper end of the spring-arm is adapted to 105 pass. 90

3. The combination, of a frame, a worm-shaft mounted therein and provided on its outer end with an operating-handle, a worm-wheel adapted to be engaged by the worm-shaft, a shrouded pinion on a common axis with the worm-wheel, a shaft having a lantern-wheel mounted thereon, the end heads of said wheel formed or provided with cogs therearound adapted to mesh with the bars 110 or spindles of the shrouded pinion, and a rack-bar, so arranged as to adapt its teeth to engage with the bars or spindles of the lantern-wheel, and to be moved vertically thereby. 115
